US0D1038949S

(12) **United States Design Patent** (10) **Patent No.:** **US D1,038,949 S**
(45) **Date of Patent:** **** Aug. 13, 2024**

(54) **COMPUTER HOST**

(71) Applicant: **Shenzhen Chuangyingxin Industrial Co., Ltd.**, Shenzhen (CN)

(72) Inventor: **Liyang Li**, Guangdong (CN)

(**) Term: **15 Years**

(21) Appl. No.: **29/942,966**

(22) Filed: **May 19, 2024**

(51) **LOC (14) Cl.** **14-02**

(52) **U.S. Cl.**

USPC **D14/439**

(58) **Field of Classification Search**

USPC D14/432, 442, 496, 385, 367, 356

CPC G06F 1/206; G06F 1/3206; G06F 1/3287

CLAIM

The ornamental design for a computer host, as shown and described.

DESCRIPTION

FIG. 1 is a front, right, and top perspective view of a computer host, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the drawings depict portions of the computer host and form no part of the claimed design.

1 Claim, 8 Drawing Sheets
